In Germany April 10, 1937

8 Claims. (Cl. 250—27.5)

Our invention relates to mercury-cathode current-converting tubes, and particularly to tubes in which an auxiliary anode arranged within a screen in the neighbourhood of the cathode mercury serves to maintain a cathode spot, and an ignition control anode arranged outside the screen serves to control the mean value of the converted current.

It is known to separate an auxiliary discharge from the discharge chamber proper by means of a screen, and use an auxiliary anode to cause this discharge to emerge from the screen and ignite the main discharge. For this purpose a voltage, which is positive with respect to the cathode, is applied at the proper moment of the alternating current cycle to an auxiliary anode arranged outside the screen. This anode causes the ignition of the main discharge at the cathode spot of the auxiliary discharge through a narrow slit provided between the screen and the level of the mercury.

Such a construction, however, has the drawback that the cathode spot of the auxiliary discharge moves to and fro inside the screen, and continuously changes its position with respect to the auxiliary anode which is located outside said screen. As a result the electrostatic conditions between the auxiliary anode and the cathode spot vary and cause irregular operation of the control device. Furthermore, difficulties are caused by the narrow slit which is present between the screen and the mercury. More particularly, due to the varying conditions of condensation, the height of the mercury level varies continuously and at a low mercury level a slit adapted to the highest mercury level acquires such a width that there is danger of premature ignition of the main discharge. At the lowest anode voltages the lines of force starting from the auxiliary anode and from the main anode itself will penetrate into the interior of the screen so that a delay in the establishment of the discharge can no longer be obtained.

The main object of our invention is to overcome the above drawbacks, and for this purpose we provide an anchoring body within a screen whose interior is accessible to the outer discharge chamber only through an opening provided immediately above the mercury, so that the inner and outer mercury surface are connected together without interruption, and arrange an ignition control anode outside this screen and in the neighborhood of the opening in such manner that the electrostatic lines of force starting there-

from pass through the opening to the interior of the screen, along a very short path.

With such a construction the cathode spot of the auxiliary discharge is always located at the same point, and excessive vaporization and movement of the cathode mercury is avoided. We have found that after the ignition, a cathode spot is generally formed outside the screen so that the control has to be considered as an ignition control device in which a cathode spot already present within the screen creates the conditions which enable the cathode spot of the main discharge to be formed at the proper moment.

The present invention differs from the usual grid control methods in that we do not employ a member through which the anode has to exert its influence in order to ignite on the auxiliary discharge so that the ignition necessarily depends on the degree to which the lines of force from the anode are able to penetrate through the controlling member, and, consequently, on the anode voltage applied. On the contrary, in the present invention the ignition control anode directly influences the auxiliary discharge to a much higher degree than the main anode does, so that the process is materially independent of the main anode voltage present at the moment. Thus the construction should be such that, even at the highest voltages that may occur, the main anode is incapable of igniting at the screened cathode spot. The ignition control anode, however, should exert such an influence in the interior of the screen that at the control voltage utilized, it is capable of establishing a discharge at the anchoring body inside the screen. As this discharge is established at an electrode outside the screen the cathode spot will have the natural tendency to displace itself in the direction of the ignition control electrode i. e. outside the screen, thus enabling the main anode to establish the main discharge at the cathode spot, immediately after the discharge has been established at the control anode, or to take it over from the ignition control electrode irrespectively of the instantaneous value of the main anode voltage, provided only that it exceeds the minimum value required for the ignition of an arc.

This independence of the main anode voltage is one of the greatest advantages of the ignition device according to the invention, because the accuracy and reliability of the establishment of the discharge are much greater than can be obtained with known forms of construction. Furthermore, the ignition device is only slightly dependent on

temperature, and its sensitiveness to harmful electrostatic or electromagnetic influences is immaterial, and the consumption of energy by the auxiliary discharge and the control is very low.

5 To increase the reliability of the ignition process according to the invention, we prefer to form the outlet of the screen as a tunnel. In this manner it is possible to reduce any excessive influence exerted by the main anode in the interior 10 of the screen and thereby fulfill the condition that the main anode can ignite without the aid of the ignition control anode at even the highest anode voltage that may occur in practice.

Particularly at very high anode voltages, we 15 prefer to still further reduce the influence exerted by the main anode on the auxiliary discharge without affecting the influence of the control anode. For this purpose we provide adjoining the tunnel-like covering, a second screen which 20 contains the ignition control anode and which also has an opening provided immediately above the mercury level, in such manner that the passageway between the outer discharge chamber and the chamber which contains the auxiliary 25 anode leads exclusively through the screen containing the control anode.

In order that the invention may be clearly understood and readily carried into effect, we shall describe the same in more detail with reference to the accompanying drawing, in which:

Figure 1 is a schematic view of a rectifying installation according to the invention, and comprising a mercury-cathode current-converting tube, sectionized along line I—I of Fig. 2,

35 Fig. 2 is a sectionized view of the tube of Fig. 1 taken along line II—II, and

Fig. 3 is a sectionized fractional view of the tube taken along the line III—III.

The tube shown in Fig. 1 has an envelope 40 comprising a vitreous portion 1 which forms three tubular projections 18, 28, and 33, and is hermetically fused at 35 to a cup-shaped metal cathode vessel 2 containing a mercury-cathode 45 4. Secured in good heat-transferring relationship to the bottom of vessel 2, for instance with hard solder, is an annular-shaped cathode-spot anchoring member 5, for instance of nickel. A 50 housing 3, secured to vessel 2 by a stud 39, which also serves as a cathode terminal, forms a space through which a suitable cooling liquid is circulated.

Extending into mercury 4 is a screen 8 of a metal such as molybdenum, or of a heat-resistant insulation material, such as steatite. As shown 55 in Figs. 1 and 2, the screen 8, which is formed of a side piece and two removable covers 9 and 10, extends over the end of the member 5 and forms two end chambers 6 and 7 connected by a passageway 60 (see Fig. 3). The interior of the screen 8 is connected to the main discharge space 60 of the tube only through an opening 11 formed between the end of the screen, the inner surface of member 5, and the surface of mercury 4.

It will be noted that the heights of opening 11 65 and passageway 60 are considerably greater than their widths, in order that variations in the level of the mercury will only slightly change the area of this opening. In the same manner, passageway 60 is defined by the top and side of screen 8, 70 the surface of mercury 4, and the inner surface of member 5.

As shown member 5 extends into the main discharge space of the tube, which enables the cathode spot to move smoothly at each new ignition 75 along the inner side of the anchoring

member 5 into the outer discharge chamber. Without this measure the cathode spot would emerge more or less in jerks due to its breaking off from the anchoring member.

Within chamber 6 is an auxiliary ignition 5 anode 12 which is adapted to be moved into and out of contact with the mercury. For this purpose, anode 12 is secured to the lower end of a metal rod 50 to whose upper end is secured a plunger 15 of magnetic material. A tube 20 10 of insulating material, such as porcelain serves to guide rod 50 and to protect the same from the discharge. A stationary iron core 17 is supported from a metal disc 19, for instance of ferrochromium, hermetically fused into the vitreous projection 18 and carrying a terminal 14. A spring 16 serves to place plunger 15 in the position shown and to carry current thereto, and a coil 21 surrounding projecting portion 18 serves to lift plunger 15 and thus to raise anode 12 from 20 the mercury.

Within chamber 7 and adjacent to passageway 60, an ignition control anode 13 is disposed laterally from the discharge path connecting the passageway 60 and the outer discharge space. 25 The ignition control anode 13 is supported from the lower end of a metal rod 25 whose upper end is secured to a metal disc 27, for instance of ferrochromium, hermetically sealed in the vitreous projection portion 28 and carrying a 30 terminal 5. Rod 25 is guided and protected from the discharge by a porcelain tube 26. It will be noted that tubes 20 and 26 also serve to hold screen 8 in position and for this purpose, the covers 9 and 10 are clamped thereto.

Coaxially arranged within the central portion of the envelope is a main anode 29 in the form of a graphite cylinder in which two vertical grooves are provided to take tubes 20 and 26. Anode 29 is supported from the lower end of a metal rod 30 whose upper end is secured to a disc 32, for instance of ferrochromium, hermetically sealed in the top of projection 33 and provided with a terminal 52. A protective tube 31 of insulating material, such as porcelain, surrounds 45 rod 30 and extends into anode 29 to protect the junction point between rod 30 and anode 29. Supported from tube 31 and supporting tubes 20 and 26 is a cylindrical screen of sheet metal which is closed at the top and serves to prevent the cathode spot, if it should leave the anchoring member 5, from climbing along the inner surface of vessel 2 and reaching the seal 35.

As shown in Fig. 1, terminal 52 of main anode 29 is connected to terminal 53 of a load 36 whose other terminal 54 is connected to terminal 55 of an A. C. supply. The other terminal 61 of the A. C. supply is connected to cathode terminal 38 to complete the rectifying circuit.

Terminal 14 of ignition anode 12 is connected 60 through coil 21, a fixed resistance 22, and a single-throw switch 23 to the positive terminal of a D. C. supply 24, whose negative terminal is connected to cathode terminal 38. Upon closure of switch 23, coil 21 is energized and lifts anode 65 12 from the mercury to thereby initiate an auxiliary discharge of about 2 amperes. For this purpose D. C. supply 24 should be of about 70 volts.

Connected across D. C. supply 24 is a potentiometer 42 having a sliding contact 56 connected through a conductor 57 to a contact 41 of a rotary contact-maker A having a second contact 58 connected to terminal 51 of the control anode 13. Fixed contacts 41 and 58 are periodically 75

connected by a rotary contact 40 driven by a synchronous motor 39 energized from the A. C. supply. For a purpose later to be referred to, contacts 41 and 58 are mounted on a ring 59 of insulating material adapted to be rotated as indicated by the double-headed arrow.

The device operates as follows:

Upon closure of switch 23, a direct current flows in the circuit of the auxiliary anode 12 and energizes coil 21 to thereby lift anode 12 from the mercury and initiate an auxiliary discharge between this anode and the cathode mercury 4 which is maintained as long as switch 23 remains closed. As long as no voltage is applied to control anode 13, this discharge cannot pass to the main anode 29 because the influence exerted by the latter in chamber 6 is insufficient to produce this result. However, when contact-maker A is placed in operation, a new discharge is set up in chamber 7 and this in turn initiates a discharge between ignition control anode 13 and the auxiliary discharge always present within chamber 6. This new discharge produces outside the chamber 6 a main cathode-spot which causes ignition of the main discharge.

The mean value of the rectified current flowing through load 36 can easily be adjusted by altering the angular position of the contacts 41 and 58 of contact-maker A, which displaces the timing of the D. C. impulses at electrode 13 with respect to each cycle of the A. C. voltage applied to main anode 29, so that the mean value of the rectified current through load 36 is altered. Although this control is in effect equivalent to the action of a control grid, it is not dependent on the voltage as is characteristic for the latter one.

It will be noted that the back ignition security of the tube may be conveniently increased by applying to the ignition control anode 13 during the blocking phase a potential which impedes the ignition of the discharge in the blocking direction, i. e. by applying a potential which is negative with respect to the cathode.

The ignition device according to the invention is particularly useful in a single-phase current-converting tube because the continuous ionization of the gas filling by the auxiliary discharge remains restricted to chamber 6 so that the security against back ignition exceeds to an appreciable extent that of a single-phase tube having an open auxiliary discharge and one of the usual control grids.

Although we have described our invention in connection with specific examples and applications, we do not wish to be limited thereto but desire the appended claims to be construed as broadly as permissible in view of the prior art.

What we claim is:

1. A current-converting tube comprising an envelope, an anode, a mercury cathode spaced from said anode to form a main discharge space, screening means forming at the surface of the mercury cathode a chamber connected to the main discharge space by an opening adjacent the surface of the mercury, means to maintain a cathode-spot including an auxiliary anode within said chamber, a cathode-spot anchoring member partly within the chamber, and means to control the mean value of the converted current including an ignition control electrode disposed near said opening but laterally from the discharge path connecting said opening and said main anode so that the electrostatic lines of force from said ignition control electrode pass through the opening and into the chamber.

2. A current-converting tube comprising an envelope, a main anode, a mercury cathode spaced from said anode to form a main discharge space, screening means formed at the surface of the mercury cathode, a chamber connected to the main discharge space through an opening, the surface of the mercury cathode forming the lower boundary of said chamber and opening, means to maintain a cathode spot including an auxiliary anode within said chamber and a cathode-spot anchoring member partly immersed in said mercury cathode, and means to control the mean value of the converted current including an ignition electrode disposed outside said chamber and laterally from the discharge path between said opening and said main anode, said cathode-spot anchoring member extending from within said screening means through the opening to the main discharge space of the tube and forming with the mercury cathode a continuous anchoring line passing through said opening in the direction of said ignition control electrode, the influence upon the starting of the main discharge of the electrostatic lines of force from the main anode and from the ignition control electrode being such that ignition of the main discharge from the auxiliary discharge is possible only by using the ignition control electrode.

3. A current-converting tube comprising an envelope, a main anode, a mercury cathode spaced from said anode to form a main discharge space, screening means forming at the surface of the mercury cathode a chamber connected to the main discharge space by a passageway adjacent the surface of the mercury, means to maintain a cathode-spot including an auxiliary anode within said chamber, a cathode-spot anchoring member partly within the chamber, and means to control the mean value of the converted current including an ignition control electrode disposed near said opening but laterally from the discharge path connecting said opening and said main anode so that the electrostatic lines of force starting from said ignition control electrode pass through the opening and into the chamber.

4. A current-converting tube comprising an envelope, a main anode, a mercury cathode spaced from said anode to form a main discharge space, an elongated cathode-spot anchoring member partly immersed in said mercury, screening means enclosing a portion of said member and forming therewith and with the mercury a chamber, a second chamber connected to the main discharge space by an opening and a passageway interconnecting said chambers, means to maintain a cathode spot including an auxiliary anode within said first chamber, and means to control the mean value of the converted current including an ignition control electrode within said second chamber and adjacent said opening, said control electrode being disposed laterally from the discharge path connecting said opening and said main anode so that the electrostatic lines of force starting from said ignition control electrode pass through said opening and into said first chamber.

5. A current-converting tube comprising an envelope, a main anode, a mercury cathode spaced from said anode to form a main discharge space, screening means forming at the surface of the mercury cathode a chamber connected to the main discharge space by an opening adjacent the surface of the mercury, means to maintain

5 a cathode-spot including an auxiliary anode within said chamber, a cathode-spot anchoring member within the chamber and extending into the discharge space, and means to control the mean value of the converted current including an ignition control electrode disposed near said opening but laterally from the discharge path connecting said opening and said main anode so that the electrostatic lines of force starting from said ignition control electrode pass through the opening and into the chamber.

10 6. A current-converting tube comprising an envelope, a main anode, a mercury cathode spaced from said anode to form a main discharge space, screening means forming a chamber at the surface of the mercury cathode, a cathode-spot anchoring member partly within the chamber and forming with said screening means an opening adjacent the mercury surface and connecting said chamber and main discharge space, means to maintain a cathode-spot including an auxiliary anode within said chamber, and means to control the mean value of the converted current including an ignition control electrode disposed near said opening but laterally from the discharge path connecting said opening and said main anode so that the electrostatic lines of force starting from said ignition control electrode pass through the opening and into the chamber.

15 7. A current-converting tube comprising an envelope, an anode, a mercury cathode spaced from said anode to form a main discharge space, screening means forming at the surface of the mercury cathode a chamber having a tunnel-

shaped opening, means to maintain a cathode-spot including an auxiliary anode within said chamber, a cathode-spot anchoring member partly within the chamber, a portion of said screening means forming a chamber connected to said opening and having a second opening adjacent the mercury surface and communicating with the main discharge space, said first chamber communicating with the main discharge space only through said second chamber, and means to control the mean value of the converted current including an ignition control electrode disposed within said second chamber.

20 8. A current-converting tube comprising an envelope, an anode, a mercury cathode spaced from said anode to form a main discharge space, screening means forming at the surface of the mercury cathode a chamber connected to the main discharge space by a single opening, the height of said opening being substantially greater than its width, means to maintain a cathode-spot including an auxiliary anode within said chamber, a cathode-spot anchoring member partly within the chamber, and means to control the mean value of the converted current including an ignition control electrode disposed near said opening but laterally from the discharge path connecting said opening and said main anode so that the electrostatic lines of force starting from said ignition control electrode pass through the opening and into the chamber.
